 of Illinois

Application March 18, 1953, Serial No. 24,082

Term of patent 3½ years

(Cl. D20—4)

To all whom it may concern:

Be it known that I, Mary F. Peck, a citizen of the United States of America, residing at Evanston, in the county of Cook and State of Illinois, have invented a new, original, and ornamental Design for a Halter Brassière, of which the following is a specification, reference being had to the accompanying drawing, forming a part thereof.

In the drawing:

Fig. 1 is a front elevation of a halter brassière showing my new design; and

Fig. 2 is a rear elevation thereof.

I claim:

The ornamental design for a halter brassière, substantially as shown.

MARY F. PECK.
